UNITED STATES PATENT OFFICE.

JOHN SAMUEL BRUCE, OF BIRMINGHAM, ENGLAND.

FASTENER FOR HINGED DOORS OR WINDOWS, SUCH AS THE DOORS OF SHOW CASES
AND THE LIKE.

Application filed December 29, 1919. Serial No. 343,206.

To all whom it may concern:

Be it known that I, JOHN SAMUEL BRUCE, a subject of the Kingdom of Great Britain, residing at Havelock Works, Holloway Head, Birmingham, in the county of Warwick, England, have invented certain new and useful Improvements in or Relating to Fasteners for Hinged Doors or Windows, Such as the Doors of Show Cases and the like, of which the following is a specification.

This invention comprises certain improvements in or relating to fasteners for hinged doors, or windows, such as the doors of show cases and the like, and refers to the type of fastener involving a vertical or longitudinal rotary member, which by rotation is adapted to retain the door or window in the closed condition, and to partially open or completely close the door by its action.

According to the present invention the said vertical or longitudinal rotary member is adapted to be actuated by or from a rotary member located at right angles thereto. This member may pass through the wood-work of the door or window so that the rotary member may be located on the rear side thereof.

In cases in which two doors or windows are adapted to close towards each other, the present invention may be adapted to retain both of said doors or windows, and the present invention may furthermore be of a character such that in the opening process one of the doors is initially displaced while at the same time the other door is maintained in its closed condition during said initial displacement, thereby ensuring that the one door is freed from the other prior to the opening of the latter.

In order that this invention may be clearly understood and readily carried into practice, reference may be had to the appended explanatory sheet of drawings, upon which:-

Figure 1 is a fragmentary elevation of a door fastener in the closed position constructed in accordance with one form of the present invention.

Figure 2 is a section taken on line $\alpha\alpha$ of Figure 1.

Figure 3 is a fragmentary elevation illus-

trating the fastener in an intermediate or midway position in the operation of fastening or unfastening the door or the like.

Figure 4 is a section taken on line $\gamma\gamma$ of 55 Figure 3.

Figure 5 is a further fragmentary elevation illustrating the fastener in the released or unfastened position the door or doors being free to open.

Figure 6 is a section taken on line $\varepsilon\varepsilon$ of Figure 5, and,

Figure 7 is a fragmentary side or edge elevation of the fastener shown in Figure 5 looking in the direction of the arrow α .

In a convenient embodiment of the present invention, the horizontal rotary member 1 which may outwardly have a suitable handle 2 or lever or key journalled in the door or frame 2^a is inwardly furnished with an 70 arm 3 adapted to oscillate the vertical rotary member 4. Said rotary member 4 comprises a pair of aligned rods 4^a which are spaced apart, and a yoke 4^b which connects their opposing ends. The arm 3 may be bifurcated as shown in Figure 7, and passing through and bridging the bifurcations a barrel or rod 8 is provided, the axis of which is parallel with the handle spindle 1 which barrel or rod 8 is adapted to rotate and slide 80 axially in relation to the bifurcations on the arm 3. Passing at right angles through the said barrel 8 and capable of a sliding movement in relation thereto is a rod 9. This rod 9 is parallel with and eccentric to the rods 85 4^a and is carried by the yoke 4^b of the rotary member 4. The connection between the handle spindle 1 and the vertical rotary member 4 thus involves four rotary axes and two sliding connections. The invention is not, 90 however, in any wise restricted to the mechanism for transmitting the movement of the horizontal rotary member 1 to the vertical rotary member 4, as this may be modified considerably.

The vertical member has an attached or integral crank part or parts 10 adapted to take behind the adjacent door or frame 11^a. There may be a part 10 at each extremity of the rotary member and a part at any 100 other desired position therein, while the said part or parts 10 may extend throughout

the entire length of the rotary member. The said part 10 at each extremity of the rotary member may comprise an arm as illustrated having a rounded extremity 11 and adapted 5 to co-operate with a rear surface 12 appertaining to the adjacent door or frame 11^a. Figures 2, 4 and 6 and also with an integral projection or lug 13 on the adjacent door or frame 11^a which projection or lug 10 extends to the rear of the said arm 10 so that when the vertical member 4 is rotated 15 to open the door 2^a the latter is forced open by co-operation of the arm 10 with the projection 13 to the rear of the same. When this projection 13 is on the adjacent door 11 as illustrated the effect of this is that said adjacent door 11^a is retained closed during the initial movement of the door 2^a by which the fastener is carried, particularly illustrated in Figures 2, 4 and 6. In these circumstances two of the projections may be provided, one 13 being mounted upon the adjacent door 11^a and the other 15 upon the framework 14. Both of these projections 13 and 15 may co-operate with one and the same arm 10 upon the rotary member 4 so that by virtue of the projection 15 which is on the frame 14 the door 2^a carrying the fastener is forced open, while by virtue of the projection 13 which is upon the adjacent door 1^a the latter is retained closed.

When there is only one hinged door say 2^a and the part 11^a is in the nature of a permanent or fixed part secured to the frame 35 14 either of the projections or lugs 13 or 15 may be dispensed with.

What I claim as my invention, and desire to secure by Letters Patent is:—

1. A hinged door or window fastener comprising a hook-shaped keeper for application to a frame or the like, a rotary member for application to a door or window and having a crank member for engagement with said hook-shaped keeper, said rotary member also having a rod parallel with and 45 eccentric to its axis, a manually operable rotary member having a crank arm provided with a slidably and revolvably mounted rod arranged at right angles to and slidably engaged with the first named rod. 50

2. A hinged door or window fastener comprising a hook-shaped keeper for application to a frame or the like, a rotary member for application to a door or window and having a crank member for engagement 55 with said hook-shaped keeper, said rotary member also having a yoke, a rod in said yoke parallel with and extending to the axis of said member, a manually operable rotary member having a crank arm provided with a 60 slidably and revolvably mounted rod arranged at right angles to and slidably engaged with the first named rod.

In witness whereof I have hereunto set my hand in the presence of two witnesses. 65

JOHN SAMUEL BRUCE.
